CLAIM

The ornamental design for an emergency communication controller and console, as shown and described.

DESCRIPTION

FIG. 1 is a front view of a first embodiment of an emergency communication controller and console according to our novel design;

FIG. 2 is a left, top perspective view thereof;

FIG. 3 is a top view thereof;

FIG. 4 is a right, bottom perspective view thereof; and

FIG. 5 is a front view thereof, where the broken lines illustrate environmental structure of the right side of the emergency communication controller and console form no part of the claimed design;

FIG. 6 is a front view of a second embodiment of the emergency communication controller and console according to our novel design;

FIG. 7 is a top view thereof;

FIG. 8 is a left, top perspective view thereof;

FIG. 9 is a right, bottom perspective view thereof;

FIG. 10 is a front view thereof, where the broken lines illustrate environmental structure of the left side of the emergency communication controller and console form no part of the claimed design.

FIG. 11 is a front view showing a possible environment of the first and second embodiments; and,

FIG. 12 a front view showing an additional possible environment of the first and second embodiments.
